Primary Examiner — John R Yeh(74) *Attorney, Agent, or Firm* — Sinorica LLC(57) **CLAIM**

The ornamental design for a mop pad, as shown and described.

DESCRIPTION

FIG. 1 is a front perspective view of a mop pad showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view of a mop pad showing my new design; and,

FIG. 9 is an enlarged view taken along lines 9 in FIG. 1, showing the looped nap and mop pad.

The broken line showing on the drawing disclosure is for illustrative purposes only and forms no part of the claimed design.

1 Claim, 7 Drawing Sheets(56)
